UNITED STATES PATENT OFFICE.

DANIEL S. BEARS, OF PROVIDENCE, RHODE ISLAND, ASSIGNOR TO RELIANCE MANUFACTURING CO., OF PROVIDENCE, RHODE ISLAND, A COPARTNERSHIP COMPOSED OF DAVID A. HART AND DEXTER E. PARTELLOW.

BELT BUCKLE.

Application filed March 12, 1924. Serial No. 698,693.

To all whom it may concern:

Be it known that I, DANIEL S. BEARS, a citizen of the United States, residing at Providence, in the county of Providence, 5 and State of Rhode Island, have invented certain new and useful Improvements in Belt Buckles, of which the following is a specification.

This invention relates to improvements in 10 belt buckles of that class in which the clamp member is pivotally mounted in the body of the buckle to engage and bind a belt therein and wherein the bail member is pivotally connected to the clamp member 15 out of alignment with the clamp pivots; and the object of this invention is to provide a clamp member in such a buckle which is formed of sheet stock and which is provided with a portion folded into eye form out of 20 axial alignment with the clamp pivots and the bail member pivotally mounted in this eye.

A further object of this invention is to 25 provide means at the joint of the bail for limiting the gripping movement of the clamp relatively to the swinging movement of the bail.

With these and other objects in view, the 30 invention consists of certain novel features 35 of construction, as will be more fully described, and particularly pointed out in the appended claims.

In the accompanying drawings:

Figure 1 is a view of the under side of a 35 buckle with my clamp and bail members pivotally connected thereto.

Figure 2 is a sectional side elevation 40 through the body of the buckle and the clamp member.

Figure 3 is a perspective view of the 45 clamping member of my improved construction.

Figure 4 is a side elevation of the clamping member showing the form in which the 50 stock is folded.

Figure 5 shows the bail member as mounted in the clamping member and engaging a finger or lug on the clamping member to prevent a relative swing of the clamp 55 towards clamping position.

Figure 6 is the same as Figure 5 and showing the clamping member as being forced to clamping position by a downward movement of the bail-member.

Figure 7 is a front view of the buckle 55 body and showing the clamping member as pivoted therein and a portion of the bail member mounted in the clamp.

It is found in the practical operation of 60 buckles of this character, of advantage to provide a bail member which has a pivoting bar extending across the same and to also provide a clamp member which may be formed of sheet stock with its edge adjacent 65 the pivot joint rolled over the bar of the bail to connect the two together, which construction of connecting the yieldable member to the bail is very inexpensive and yet is very strong and durable; and the following is a detailed description of one 70 means by which these advantageous results may be accomplished:

With reference to the drawings, 10 designates the body of a buckle, which is preferably formed of sheet stock having rearwardly-extending walls 11 and inwardly-turned buckle guiding flanges 12.

These side walls 11 are also provided with 75 ears 13 which are pierced to receive the pivot 80 pintles 14 on the clamping member 15. This clamping member is formed of sheet stock and in some cases, is provided with a plurality of biting or gripping surfaces 16, and it is also provided with laterally extending 85 pivot pins 14 adapted to extend through the eyes 13 of the body and the upper edge of this clamping member is rolled back to form an eye 18, the axis of which is above or out of alignment with the axis of the 90 pivot pins 14.

By this construction of forming an eye by folding or rolling the stock of the clamping member, I am enabled to provide a bail member 19 with a pivot bar 20 extending 95 across between its side arms 21 and over which the stock of this eye portion is rolled to loosely or pivotally connect the bail to the clamp, which construction is very practical from a manufacturing standpoint inasmuch as it is a very inexpensive operation to assemble the parts and also is very strong and durable and the parts when once assembled cannot be separated even by extraordinary strains applied to the belt parts.

It is found in the construction of a clamping unit of this character, of advantage to provide means at the joint to limit the swing of the 100 clamp relatively to the swing of the

bail and to accomplish this in a simple and effective way, I have formed extensions, fingers or lugs 22 on the upper edge of the clamping member which project rearwardly 5 as shown and provide a stop or rest against which portions of the bail rest to the area of its pivoting center, whereby a lifting movement of the bail will swing the clamp on its pivots 14 from clamping position to release 10 the belt and permit it to be freely withdrawn from the buckle.

By my improved construction, I also form the forward edge 23 of the clamp in such a manner that it will engage the side arms 21 15 of the bail to prevent excessive outward swing of the clamp.

My improved clamping unit for belt buckle is very simple and practical in its construction and effective in its operation 20 and by its use a belt in the buckle will be clamped and firmly held in position and at the same time can be readily released by an opening movement of the bail when desired.

The foregoing description is directed 25 solely towards the construction illustrated, but I desire it to be understood that I reserve the privilege of resorting to all the mechanical changes to which the device is susceptible, the invention being defined and 30 limited only by the terms of the appended claims.

I claim:

1. A buckle having a body portion, a sheet

metal belt-clamp pivotally supported in the body and having a portion folded into eye- 35 form out of axial alignment with the clamp pivots, a bail member having a bar pivotally mounted in said eye, and means adjacent the pivot of the bail for limiting the gripping movement of the clamp relatively to the 40 movement of the bail.

2. A buckle comprising a body portion, a sheet metal clamp-member having pivot trunnions rotatably mounted in said body 45 with an integral eye-portion formed thereon out of axial alignment with the trunnions, a bail member mounted to swing in said eye, and lugs on one of said members to be engaged by the other of said members for limiting the gripping movement of said clamp 50 member and whereby said bail may be operated to move said clamp to belt-releasing position.

3. A buckle having a body portion, a sheet metal clamp member pivotally supported in the body and having an integral eye-portion 55 formed thereon out of alignment with the clamp pivots, a bail member mounted to swing in said eye, stop lugs integral with said clamp and located at each end of said eye portion to engage the bail member when in operative position and limit the belt gripping movement of the clamp relatively thereto.

In testimony whereof I affix my signature.

DANIEL S. BEARS.
